UNITED STATES PATENT OFFICE.

ESTELLE V. ALLISON, OF NEW YORK, N. Y.

ADVERTISING WRITING-TABLET.

1,370,871.

Specification of Letters Patent.

Patented Mar. 8, 1921.

Application filed December 10, 1919. Serial No. 343,981.

To all whom it may concern:

Be it known that I, ESTELLE V. ALLISON, a citizen of the United States, residing at the city of New York, in the county of New York and State of New York, have invented certain new and useful Improvements in Advertising Writing-Tablets, of which the following is a specification.

My invention relates to improvements in advertising writing tablets and the object of my invention is to provide a simple, convenient and efficient writing tablet which may be used for advertising purposes and the like.

I accomplish this object by the device illustrated in the accompanying drawings in which—

Figure 1 is a perspective view of the device.

Fig. 2 is a section of the same on the line 2—2 in Fig. 1.

Fig. 3 is a detailed sectional perspective view illustrating the arrangement of the sections of the tablet.

My improved device comprises two counterpart covers 1, 1 each of which covers is preferably identical on the front and back sides and comprises a central panel 2 and a plurality of surrounding panels 3, 4, 5, 6, 7 and 8 in symmetrical arrangement. The said panels are adapted to contain suitable advertising matter or other data as may be desired. Between the covers 1 I provide a plurality of writing sheets 9 detachably bound at the hinge 10 of the covers and preferably so faced that approximately one-half in number of the writing sheets 9 are faced toward each of the covers 1 and these writing sheets 9 may be provided with any de-

sired form of letterheading or the like in the usual well known manner. This arrangement of the front faces of the sheets 9 form two separate sections 11 and 12 of the leaves, the leaves of each section facing outwardly from the center of the tablet.

The device being thus assembled it will be apparent that the two sides or faces may be used interchangeably as the top or front of the device and irrespective of whether the device is open or closed and irrespective of which side or face is uppermost the entire advertising matter or other data contained in the panels will be presented to view, and as the writing sheets contained within the covers are faced toward both covers, the tablet is ready for use in either positions and has in effect two fronts with no back.

Having thus described my invention what I claim is:

1. A tablet of writing paper comprising covers and leaves disposed between the covers in sections, the leaves being provided with indicia on one face only adjacent one edge, and the leaves of one section being faced toward one cover and the leaves of the other section being faced toward the other cover.

2. A tablet of writing paper comprising covers having thereon a plurality of panels arranged to receive advertising matter, and leaves disposed between the covers in sections, the leaves being provided with indicia on one face only adjacent one edge, and the leaves of one section being faced toward one cover and the leaves of the other section being faced toward the other cover.

In testimony whereof I affix my signature.
ESTELLE V. ALLISON.
